UNITED STATES PATENT OFFICE

HENDERIKUS JACOBUS VERWAYEN, OF ASTORIA, NEW YORK

DESIGN FOR A VASE

Application filed January 13, 1930. Serial No. 34,116. Term of patent 3½ years.

To all whom it may concern:

Be it known that I, HENDERIKUS JACOBUS VERWAYEN, a subject of the Netherlands, residing at Astoria, Long Island, in the county of Queens and State of New York, have invented a new, original, and ornamental Design for Vases, of which the following is a specification, reference being had to the accompanying drawing, forming part thereof.

Fig. 1 is a side view of a vase showing my new design.

Fig. 2 is a front view thereof.

I claim:

The ornamental design for a vase as shown.

HENDERIKUS JACOBUS VERWAYEN.
